UNITED STATES PATENT OFFICE.

CASIMIR VON PHILP, OF BETHLEHEM, PENNSYLVANIA, ASSIGNOR TO BETHLEHEM STEEL COMPANY, OF SOUTH BETHLEHEM, PENNSYLVANIA, A CORPORATION OF PENNSYLVANIA.

APPARATUS FOR STORING AND CONVEYING LIQUID METALS.

No. 810,301.

Specification of Letters Patent.

Patented Jan. 16, 1906.

Application filed May 20, 1904. Serial No. 208,952.

To all whom it may concern:

Be it known that I, CASIMIR VON PHILP, a citizen of the United States, residing at South Bethlehem, Northampton county, State of Pennsylvania, have invented certain new and useful Improvements in Apparatus for Storing and Conveying Liquid Metal, of which the following is a specification.

The present invention comprises an apparatus suitable for receiving and storing liquid metal, for keeping the same heated and in liquid condition until poured off, and for transferring the metal from one place to another.

15 The apparatus may be used for transferring liquid metal from blast-furnaces or cupolas to puddling-furnaces, open-hearth furnaces or foundries, or for any other operations in which it is necessary to move liquid metal from one place to another or to keep the metal in liquid condition for any length of time.

20 The apparatus will be described in connection with the accompanying drawings, in which—

25 Figure 1 is a plan view of the apparatus. Fig. 2 is a longitudinal central section on the line A A of Fig. 1. Fig. 3 is an end view, and Fig. 4 is a section on the line B B of Fig. 1.

30 Referring to the drawings, C indicates the body of the storing vessel, and D the cover. The middle portion 1 of the body is semicircular and adapted to receive the liquid metal. At each end the bottom is inclined upward, 35 as at 2, and the body terminates in substantially cylindrical extensions 3, having mixing and burning chambers x x therein. The body comprises a metal shell 4, strengthened by suitable ribs 5 and provided throughout 40 with a refractory lining 6. In the ends and at suitable points on the sides of the body are burners 7 for producing heat in the vessel by means of oil, gas, or other suitable fuel which is injected with air into the chambers x and 45 above the molten metal and is burned, the combustion retaining the whole body of metal in a molten condition as long as required. On the sides of the vessel about midway of its height are discharge-openings 50 8, provided with suitable pouring-spouts 9.

80 The lid D is preferably arched and of a construction similar to the body of the vessel—that is, having a shell 10, of metal, strength-

ened by suitable ribs 11 and lined with refractory material 12. Lugs are provided on the body and on the lid to receive bolts 13, by means of which the lid may be securely attached to the body. Other lugs 14 are provided by means of which the lid may be lifted. In the top of the lid are one or more inlet-openings 15, through which the liquid metal is poured into the vessel. The lid extends over the body portion of the vessel between the inclines 2, and the cylindrical extensions 3 are permanently closed on top.

45 The apparatus is in the general form of a car, the body or vessel resting on wheeled trucks 16 17 of any suitable construction and provided with a suitable connecting-frame 18 and couplings 19. On a platform extension 18^a of frame 18 over each truck is a transverse rack 20, and meshing with this rack is a sector-gear 21, connected with a yoke 22, in which the cylindrical extension 3 of the body rests. A partial wheel 21^a, connected 50 with segment 21, supports the yoke 22 and the vessel. The wheel 21^a runs on a rail 20^a on the platform adjacent to the rack 20. The body is thus supported by the rails 20^a, and the racks and sector-gears prevent lateral 55 sliding movement on the truck, but permit the vessel to be rocked to pour the liquid metal from the side openings.

60 The apparatus for rocking or tipping the vessel consists of suitable gearing, as follows: 85 Rigidly connected to one end of the vessel is a large segmental gear 23, which is turned by a worm 24, the worm being turned by power transmitted through a suitable train of gearing from a hand-wheel or crank 25. 90 The segmental gears 21 and 23 have a common center, (indicated at 26,) and said gears are therefore always in proper engagement with the worm 24 and the rack 20. It will be understood that the vessel is similarly 95 equipped at each end with yoke 22, segmental gear 21, and rack 20.

65 In the use of this apparatus the vessel may be filled with liquid metal up to or nearly to the outlet-openings 8. As will be seen, this leaves the upper and larger part of the vessel for use as a combustion-chamber for the oil or gases used to keep the metal hot. The spent gases escape through the inlet-openings 15.

70 It will be noted that the burners are all di-

rected toward the middle portion of the vessel in which the metal is contained and that the openings 15 are somewhat centrally arranged in the cover, thus permitting of a 5 concentration of the heat over the metal.

By the use of this apparatus the metal may be carried to any desired point and discharged, or discharged at different points, or stored in a molten condition for any desired 10 length of time. The gases, oil, or other fuel may be supplied from any suitable source—for instance, from a car coupled to the conveying apparatus and running on the same track.

15 Having described my invention, what I claim as new, and desire to secure by Letters Patent, is—

1. An apparatus for storing and transporting molten metal consisting of a vessel 20 and suitable trucks supporting the same, the vessel having an enlarged body portion and hollow contracted cylindrical ends containing burning-chambers and means for admitting fuel thereto, said ends turning in bearings on the trucks, substantially as set forth.

2. In an apparatus for storing and transporting molten metal, the combination of 25 two trucks and a receptacle having a central portion extending downward between the trucks and hollow end portions extending over the trucks and adapted to turn in

bearings on the trucks, substantially as set forth.

3. In an apparatus for storing and transporting molten metal, the combination of 35 two trucks and a receptacle having a central portion extending downward between the trucks and hollow end portions extending over the trucks and adapted to turn in bearings on the trucks, and pouring-spouts 40 on the body portion, substantially as set forth.

4. In an apparatus for storing and transporting molten metal, the combination of 45 two trucks, a receptacle having a central portion extending downward between the trucks and hollow end portions extending over the trucks and adapted to turn in bearings on the trucks, a sector-gear 50 20 on one of the end portions, a transverse rack on the truck engaged thereby, a larger concentric sector-gear on said end portion, and a worm engaging the latter gear and turning in bearings of the truck, substantially as set forth.

In testimony whereof I have signed my 55 name to this specification in the presence of two subscribing witnesses.

CASIMIR VON PHILP.
